DESIGN FOR A SADDLE RIGGING

Oscar Larson, Vallejo, Calif.

Application July 29, 1944, Serial No. 114,623

Term of patent 14 years

(Cl. D38—7)

To all whom it may concern:

Be it known that I, Oscar Larson, a citizen of the United States, residing at Vallejo, in the county of Solano, and State of California, have invented a new, original, and ornamental Design for a Saddle Rigging, of which the following is a specification, reference being had to the accompanying drawing, forming part thereof.

Figure 1 is a top plan view of a saddle rigging showing my new design, and

Figure 2 is an edge elevational view thereof.

I claim:

The ornamental design for a saddle rigging, as shown.

OSCAR LARSON.
